(57) **CLAIM**

The ornamental design for a digital picture display ornament with LEDs, as shown and described.

DESCRIPTION

FIG. 1 is a front view of a digital picture display ornament with LEDs showing my new design;

FIG. 2 is a rear view thereof; and,

FIG. 3 is a perspective view.

The broken lines of FIGS. 1-3 are for environmental purposes only and form no part of the claimed design.

1 Claim, 2 Drawing Sheets

FIG. 1

FIG. 2

FIG. 3
